US0D1107667S

(12) **United States Design Patent** (10) **Patent No.:** **US D1,107,667 S**
(45) **Date of Patent:** ** *Dec. 30, 2025

(54) **CONTROL DEVICE**

- (71) Applicant: **Lutron Technology Company LLC**,
Coopersburg, PA (US)
- (72) Inventors: **Gregory Altonen**, Easton, PA (US);
Susan Hakkarainen, Doylestown, PA (US); **Jason C. Killo**, Emmaus, PA (US); **Brad Michael Kreschollek**, Bethlehem, PA (US); **Noel Mayo**, Philadelphia, PA (US); **Matthew Philip McDonald**, Phoenixville, PA (US)
- (73) Assignee: **Lutron Technology Company LLC**,
Coopersburg, PA (US)
- (*) Notice: This patent is subject to a terminal disclaimer.
- (**) Term: **15 Years**
- (21) Appl. No.: **29/986,025**
- (22) Filed: **Jan. 17, 2025**

Related U.S. Application Data

CLAIM

The ornamental design for a control device as shown and described.

DESCRIPTION

FIG. 1 is a front perspective view of a control device showing our new design;

FIG. 2 is a front view thereof; and,

FIG. 3 is a side view thereof.

1 Claim, 2 Drawing Sheets
